UNITED STATES PATENT OFFICE.

GOTTLÖB FUEGEL AND HERMAN SCHMID, OF BROOKLYN, NEW YORK, ASSIGNEES, BY
MESNE ASSIGNMENTS, TO APOLLO MAGNETO CORPORATION, OF BROOKLYN, NEW
YORK, A CORPORATION OF DELAWARE.

KEY.

1,417,161.

Specification of Letters Patent. Patented May 23, 1922.

Application filed August 30, 1919. Serial No. 320,915.

To all whom it may concern:

Be it known that we, GOTTLÖB FUEGEL and HERMAN SCHMID, who were formerly subjects of the German Empire, but who have severally renounced all allegiance to said power and declared our intentions of becoming citizens of the United States, residing in Brooklyn, in the county of Kings and State of New York, have invented certain new and useful Improvements in Keys, of which the following is a specification.

Our invention relates to an improvement in keys; particularly keys for securing part of a mechanical construction in adjusted position.

An object of our invention is to provide a key having a portion that is especially adapted to engage the part or member to be secured and maintain it in the position desired.

Other objects and advantages of our invention are set forth in the following description, taken in connection with the drawings, which disclose the best form of our invention now known to us; and the characteristics of our invention are precisely defined in the appended claim. This disclosure, however, is explanatory only, and we may employ embodiments of our invention other than what is actually shown herein, but within the scope and spirit of our invention as the same is indicated by the general meanings of the terms in which the claim is expressed and by the variations in the phrasing of the same.

On the drawings:

Figure 1 is a side view of a key according to our invention;

Figure 2 is a rear end view and Figure 3 a front end view of same; and

Figure 4 is a view showing the key in operative position, with the part held by it, in section.

The same numerals identify the same parts throughout.

Our key is shown at 1 with a kerf 2 at one end, and threads 3 at the other. Instead of a kerf, the key may be otherwise shaped to enable a tool to be utilized to turn the key. Between the ends of the key is a portion 4, having projections 5, to roughen it. The key may taper towards the threads 3, and the portion 4 is preferably conical, with the projections 5 in the form of points or ribs,

to impart a frictional surface to the portion 4, and make this portion capable of engaging the part to be secured, in a proper and efficient manner.

In practice the key is put into use as illustrated in Figure 4. That view shows a bearing sleeve or member 6, having an eccentric bore, and being encircled on its exterior by a groove 7. Usually the sleeve 6 is slipped on a shaft, not shown; and is disposed in a bushing 8, placed in a support 9. This bushing permits the sleeve 6 to be adjusted therein by turning the sleeve and two keys according to our invention, are employed to hold the sleeve 6 fast after the desired adjustment is obtained. At the upper end the bushing 8 has a groove 10, and at its lower end it has a recess 11. This recess extends through the lower end of the bushing and is intended to register with the adjacent portion of the groove 7. The grooves 7 and 10 and the recess 11 are preferably in the same vertical or transverse plane with respect to the axis of the sleeve 6; and the keys 1 are inserted through bores 12 in the support 9, one to engage the groove 10 and the other to enter both the groove 7 and recess 11. When turned up, one of these keys will cause its projections 5 to be pressed tightly against the bushing 8 above, and the other will similarly bind with its projections 5 extending through the recess 11 in the bushing 8 against the surface of the groove 7 below; and thus the member 6 will be held against movement. Of course the bores 12 are in the same plane as the grooves 7 and 10 and recess 11.

The shaft mounted in the sleeve 6 will ordinarily be the distributor shaft of a magneto for the ignition system of an internal combustion engine, although our invention is by no means limited to such a device, but may be employed in connection with many other constructions. When it is desired to adjust the position of the shaft in this sleeve, as by moving its axis up or down with reference to Figure 4, the lower key 1 is loosened and the sleeve turned; and then the lower key is again tightened to make its projections 5 press firmly against the surface of the groove 7. Then the sleeve 6 cannot be moved, and the position of the shaft remains fixed till the operator once more turns back the key 1.

- It will be noted that the upper end of the bushing 8 is thicker than the lower end. Therefore, if one has to move the axis of the shaft in the sleeve 6 a relatively great distance upward, he can take out both keys and invert the bushing 8. The sleeve 6 will then be carried higher, and the upper key will be the one binding in the groove 7, the lower key engaging with the groove 10, which will now be at the bottom. Adjustment of the sleeve 6 can be had in this case, as before, by loosening the upper key, turning the sleeve and again tightening the upper bolt.
- 15 A key as above described can be easily and quickly made either by cutting threads, ribs or ridges on the portion 4, or by punching this portion to provide points 5 as shown; and a key of this type co-operates excel-

lently with the sleeve 6 and bushing 8 to give 20 the wished-for result.

Having described our invention, what we believe to be new and desire to secure and protect by Letters Patent of the United States is:

25 A key having one end shaped to be engaged by a tool and having threads at its opposite end, said key including a tapering portion between its ends, with projections substantially surrounding a part of said portion to provide a frictional surface to engage and hold a member in a desired position.

30 In testimony whereof, we have signed our names to this specification this 22nd day of May, 1919.

GOTTLOB FUEGEL,
HERMAN SCHMID.
